UNITED STATES PATENT OFFICE.

LEWIS J. ATWOOD, OF WATERBURY, CONNECTICUT, ASSIGNOR TO THE PLUME & ATWOOD MANUFACTURING COMPANY, OF SAME PLACE.

DESIGN FOR A LAMP-STAND.

SPECIFICATION forming part of Design No. 23,967, dated January 29, 1895.

Application filed December 20, 1894. Serial No. 532,499. Term of patent 7 years.

To all whom it may concern:

Be it known that I, LEWIS J. ATWOOD, a citizen of the United States, residing at Waterbury, in the county of New Haven and State of Connecticut, have invented a new Design for a Lamp-Stand, of which the following is a specification.

The leading feature of this design consists in the design of the compound curved handles-legs that connect the lamp holding rings.

In the drawings: Figure 1 is an elevation, and Fig. 2 a plan view of the stand.

The upper lamp holding ring *a*, and lower

ring *b*, are circular. The legs *c*, have scroll feet 2, loops 3, at their upper ends and scrolls 15 at 4.

I claim—

The design for a lamp stand substantially as described and shown.

Signed by me this 14th day of December, 1894.

L. J. ATWOOD.
